UNITED STATES PATENT OFFICE.

HORACE G. SLOAN, OF CHICAGO, ILLINOIS, ASSIGNOR TO THOMAS E. COPELIN, OF CHICAGO, ILLINOIS.

ADVERTISING DEVICE.

1,178,185.

Specification of Letters Patent.

Patented Apr. 4, 1916.

Application filed June 13, 1914. Serial No. 844,861.

To all whom it may concern:

Be it known that I, HORACE G. SLOAN, a citizen of the United States, and a resident of Chicago, in the county of Cook and State 5 of Illinois, have invented a certain new and useful Improvement in Advertising Devices, of which the following is a specification.

This invention relates to advertising devices.

10 The object of the invention is to provide an effective transparency advertising device in connection with a well known form or type of humidor, comprising a receptacle for water and an incandescent electric lamp 15 submerged therein for promoting evaporation, constituent parts of which are utilized as parts of said advertising device. To this end, an advertising device of my invention comprises the various features and details 20 of construction hereinafter described and claimed.

In the accompanying drawing, in which my invention is fully illustrated, Figure 1 is a perspective view of an advertising device 25 vice of my invention. Fig. 2 is a vertical longitudinal sectional view thereof on the line 2—2 of Fig. 3. Fig. 3 is a transverse vertical, sectional view thereof on the line 3—3 of Fig. 2; and Fig. 4 is an enlarged 30 fragmentary detail of the lamp supporting means.

Referring now to the drawings 1 designates the water receptacle of a well known form of humidor, evaporation of the water 35 contained therein being promoted by an incandescent electric lamp 2, which, in use, is adapted to be submerged in the water contained in said receptacle. In the preferable construction shown, said lamp 2 is removable 40ably mounted on the receptacle 1 in such manner that it may be submerged more or less, as more or less evaporation is desired. The means for thus supporting said lamp consists of a plate 3 hinged to the receptacle 45 1, preferably to the upper edge of one end thereof, the hinge of said plate being quite stiff so that said plate will stay in any adjusted position corresponding to more or less submergence of the lamp 2. Said lamp 50 2 is connected to said plate preferably in such manner that said lamp may be quickly and conveniently attached to or detached from said humidor. As shown, said lamp is adapted to be connected to said plate by 55 springs 4 secured to said plate with their

free ends projecting upward, thus forming a spring clip adapted to receive the socket 5 of said lamp.

As regards its general features, both the construction and operation of the type of 60 humidor described are old and well known and no claim is made to the exclusive use thereof, excepting as parts or elements thereof are embodied in and form part of my improved advertising device as I shall 65 now describe.

Supported on the vessel or receptacle 1, as a base, is a skeleton frame 6, which is adapted to receive a plate or panel 7 of transparent or translucent material, on 70 which is reproduced or depicted any desired advertisement, as indicated. Preferably said plate or panel 7 is clear glass and the advertisement may be applied directly thereto in the form of a decalcomania or transfer 75 picture, but is preferably printed or engraved on a separate sheet of paper pasted or otherwise secured thereto. As shown, said frame 6 is provided with marginal flanges 8 which define a seat for the plate or panel 7 80 and said frame is supported on rods 9 secured to the corners of the receptacle 1 and which project above the top of said receptacle, the rear rods projecting somewhat higher than the front rods, thus supporting 85 the frame 6 and plate or panel 7 in inclined position.

With the described construction, it is obvious that the lamp 2 will be located directly beneath the plate or panel 7, thus forming 90 a transparency which will bring out the advertisement on said plate or panel very conspicuously. Also, said plate or panel 7 will form in effect a cover for the receptacle 1 and will prevent articles, as cigars, from 95 falling into the same.

I claim:

1. A humidor and advertising device comprising a receptacle for containing water, a panel of non-opaque material supported over the top thereof adapted to receive an advertisement, and an incandescent electric lamp supported in said receptacle in position to be immersed in the water contained therein and adapted for illuminating the panel supported over said receptacle, substantially as described. 100

2. A humidor and advertising device comprising a receptacle for containing water, a skeleton frame supported on said receptacle, 105

110

a panel of non-opaque material secured in said frame and which extends over the top of said receptacle and which is adapted to receive an advertisement, and an incandescent electric lamp supported in said receptacle in position to be immersed in the water contained therein and adapted for illuminating the panel supported above said receptacle, substantially as described.

In testimony that I claim the foregoing as my invention, I affix my signature in the presence of two subscribing witnesses this 23d day of May, 1914.

HORACE G. SLOAN.
